[57] **CLAIM**

The ornamental design for a microwafer system for processing and storing audio visual information, as shown and described.

DESCRIPTION

FIG. 1 is an exploded perspective view of a microwafer system for processing and storing audio visual information showing my new design;

FIG. 2 is a top plan view thereof;

FIG. 3 is an exploded front elevational view thereof, the rear elevational view being identical in appearance;

FIG. 4 is a bottom plan view thereof; and,

FIG. 5 is an end elevational view thereof, the opposite end elevational view being identical in appearance.

The broken lines shown in the views are shown for illustrative purposes only and form no part of the claimed design.

FIG. 1

FIG. 2

FIG. 4
